No. 690,363.

Patented Dec. 31, 1901.

C. ESSER.

APPARATUS FOR THE PRODUCTION OF HALF STUFF FROM PEAT.

(Application filed Aug. 9, 1901.)

(No Model.)

UNITED STATES PATENT OFFICE.

CHRISTIAN ESSER, OF WIENER NEUSTADT, AUSTRIA-HUNGARY, ASSIGNOR
OF ONE-HALF TO ADOLF POLLAK, OF VIENNA, AUSTRIA-HUNGARY.

APPARATUS FOR THE PRODUCTION OF HALF-STUFF FROM PEAT.

SPECIFICATION forming part of Letters Patent No. 690,363, dated December 31, 1901.

Application filed August 9, 1901. Serial No. 71,495. (No model.)

To all whom it may concern:

Be it known that I, CHRISTIAN ESSER, chief manager of a paper-mill, a citizen of the Empire of Germany, residing at Wiener Neustadt, Austria-Hungary, have invented certain new and useful Improvements in Methods of and Apparatus for the Production of Half-Stuff from Peat-Turf; and I do hereby declare the following to be a full, clear, and exact description of the invention, such as will enable others skilled in the art to which it appertains to make and use the same.

The methods hitherto in use for the production of half-stuff from peat-turf give rise to the objection that the finer parts or fibers are destroyed if the action of the process is allowed to continue till all the fibers have been completely loosened from the coarser parts. In consequence of this proceeding it usually happens that during the further treatment (alkali treatment) into paper of the half-stuff thus obtained the completely-destroyed fine particles of the peat-turf settle and form an impervious layer at the bottom of the sieve and, moreover, are incapable of felting, owing to their shortness of fiber. Not only is the sluggish outflow of the water the direct cause of the slow speed of the paper-mill, but the article produced is altogether of low quality by reason of the faulty felting capability of the smaller particles of the half-stuff.

This invention has for its object to provide a mechanical arrangement for loosening the fibers from peat-turf for use in the manufacture of paper, which broadly consists in subjecting the turf to the mechanical action of stampers, whereby the coarser parts of it are completely flattened and defibered without the destruction of the finer or weaker fibers.

The operation may be effected by any convenient stamping apparatus; but it is advisable to use for this purpose the specially-designed stamping apparatus shown in the accompanying drawings, in which—

Figure 1 is a vertical section, and Fig. 2 a plan, of the improved stamping-mill.

According to our invention we provide a rotary circular table 1, supported upon a series of conveniently-disposed rollers *b* and provided with a peripheral toothed rack *c*, driven

from the shaft *v* by means of appropriate gears *d f* and *h i*, in conjunction with the intermediate shaft. The said table 1 forms the bottom of a stationary cylindrical vat 4, fitted with a central cylindrical part 5 in such a manner as to form between the two cylindrical parts 4 and 5 an annular space, the bottom of which is formed by a stone lining 2, carried on the table 1.

Above the table 1 are provided two cross-wise-arranged vertical bows 6 6, which rest on symmetrically-disposed standards 7, externally of the cylinder 4. Each arm of the bows 6 is fitted with two sets of plummer-blocks 8 8, in which are mounted shafts *v w*. In the center of the bows *b* is seated a vertical shaft with a beveled toothed wheel *n*, which latter is driven by similar wheels or pinions on the shafts *v*, mounted in the upper part of the plummer-blocks 8 and also imparting motion to the shaft *g* for rotating the table. The other shafts *v* in the upper parts of the plummer-blocks 8 receive motion from the centrally-disposed wheel *n* and transmit the motion, through the intervention of a gear *s t*, to the corresponding lower shafts *w*, causing the latter to rotate in the opposite direction.

To each side of each pair of plummer-blocks 8 8 and of the arms of the bows 6 are fixed 80 guide-plates 9 10 for the stampers *p p p q q q*. In these guides 9 10 are guided on both sides of each pair of shafts three stampers *p p p q q q*, which, with their pins *u u*, project in the path of the cams *o o*, mounted on the 85 shafts *r w*, whereby the stampers are intermittently lifted and dropped. The stampers *q q q* on the one side of the shafts receive motion from the upper shaft *v*, and the stampers *p p p* on the other side of such shafts receive 90 motion from the lower shaft *w*. The faces of the stampers *p q* are formed of wooden blocks *j*, while the bottom of the rotary table 1, on which the stampers fall, is, as already mentioned, furnished with a stone lining 2. 95

In front of each series of stampers is provided a blade or scraper *k*, hinged to the outer cylinder and serving to smooth the surface of the material after being disarranged by the blows of the stampers.

At a suitable part of the stationary outer casing 4 is fixed a plate *a* for discharging the

sufficiently-treated peat-turf, the said plate dipping down to the surface of the table 1 and the casing 4 having a discharge-opening z , normally closed.

5 The operation of our improved apparatus is as follows: The peat-turf, in order to loosen the fibers, is spread upon the table in a layer 3 of five to ten centimeters thick, which may be effected by any appropriate automatic 10 charging mechanism. In starting the apparatus the table is rotated, and in this manner the material placed thereon is carried around underneath the stampers, which perform about one hundred to two hundred and fifty 15 strokes per minute. When the peat-turf has been sufficiently treated, the dipping-plate a is placed in position and the door of the discharge-opening z opened, so that the said material is thrown by the rotating table against 20 the plate a and finally discharged through the opening z . The action of the stampers on the peat-turf is such as to crush only the coarse parts thereof between the wooden faces of the stampers and the stone surface of the table, 25 and thus loosen all the fibers of these coarse parts, while the fine parts, which are already suitable for working into half-stuffs, are protected by the thicker parts from the action of the stampers, and thus remain uninjured. 30 By this mechanical treatment of the peat-turf in the herein-described apparatus the useless extraction of the fibers from the weaker parts is completely retarded, and only those parts are reduced which are otherwise unsuitable for the production of half-stuffs. 35

It must be well understood that the apparatus shown in the annexed drawings is merely an example of a constructional form,

as the principle of the invention, according to the opening statement, consists in the 40 method of extracting the fibers of the peat-turf for the production of half-stuffs mechanically by the action of stampers.

Having thus fully described my invention, what I claim, and desire to secure by Letters 45 Patent of the United States, is—

1. A machine for stamping peat-turf comprising a stone-faced table of annular form with inner and outer walls, a series of stampers located therein, means for reciprocating 50 the stampers, and radial scrapers hinged to the outer wall and raised a slight distance above the table, substantially as described.

2. A machine for stamping peat-turf comprising a stone-faced table of annular form 55 with inner and outer walls, a series of stampers located therein, means for reciprocating the stampers, a vertical plate extending across the annulus, a discharge-opening in the outer wall of the annulus adjacent to said 60 plate, and means for closing said opening, substantially as described.

3. A machine for stamping peat-turf comprising an annular table, two radial shafts one above the other above the table, a series 65 of stampers along each side of said shafts, means on the upper shaft for operating one series of stampers, and means on the lower shaft for operating the other series of stampers, substantially as described.

In testimony whereof I affix my signature in presence of two witnesses.

CHRISTIAN ESSER.
